UNITED STATES PATENT OFFICE.

THOMAS JAMES, OF BRADDOCK, PENNSYLVANIA.

CRANE.

SPECIFICATION forming part of Letters Patent No. 591,650, dated October 12, 1897.

Application filed February 16, 1894. Serial No. 500,369. (No model.)

To all whom it may concern:

Be it known that I, THOMAS JAMES, of Braddock, in the county of Allegheny and State of Pennsylvania, have invented a new and useful Improvement in Cranes, of which the following is a full, clear, and exact description, reference being had to the accompanying drawings, in which—

Figure 1 is a front elevation of my improved charging apparatus, showing a part only of the mast or upper framework. Fig. 2 is a front elevation, on a larger scale, of the upper part of the apparatus. Fig. 3 is a side elevation thereof. Figs. 4 and 5 are enlarged detail views. Fig. 6 is a side elevation on the side opposite to that of Fig. 3, and Fig. 7 is a vertical section on the line VII VII of Fig. 6.

Like symbols of reference indicate like parts in each of the views.

The object of my invention is to provide a furnace charging and drawing apparatus possessing new and useful properties and functions not afforded by prior devices used for the same general purpose.

In the drawings, 2 represents the bridge or jib of a traveling crane, mounted on wheels 3 upon an overhead track 4, on which it is adapted to be driven back and forth by a motor 5, connected with the axle by gearing 6.

7 is a trolley or carriage set on the bridge and movable thereon by a motor 8, connected by gearing 8' with the axle of the trolley. The motors 5 and 8 are preferably electric motors. On the trolley 7 is an upright guide-frame 9, in which is set a vertically-movable post 10, fitted with counterbalancing-weights 11 and chains 12, which pass over pulleys 13 on the guide-frame.

To the lower end of the movable post 10 is fixed the head of tongs whose jaws 14 are pivoted at points 15 and are connected by toggle-levers 16 or otherwise to the piston-rod 17 of a cylinder 18, which is set on the movable post 10 and is actuated by fluid-pressure, the fluid used being preferably air, though steam or liquid may be employed for this purpose. When air is used, it is supplied from the reservoir 19, which is carried by the trolley or crane-bridge and is supplied by a pump 20, driven through gearing 20' by an electric motor 21. The rheostat 22 of the motor which drives the pump is connected

by levers 23 or other suitable mechanism to the piston or governor 24 of a small cylinder 24', which is connected by a fluid-passage 25 to the air-reservoir, so that when the pressure in the air-reservoir reaches a certain predetermined degree the cylinder or governor will raise the lever 23 and will move the rheostat so as to stop the motor, and when the pressure is again reduced in the air-reservoir a counterweight 26 moves the lever in the opposite direction and operates the rheostat so as to start the motor again into action.

27 is a valve controlling the passage of air from the reservoir 19 of the cylinder 18. This valve may be operated by a system of levers or rods 28 or any other suitable device.

In order to move the post 10 vertically, I employ a pinion 29, which is driven by a motor 30 and meshes with a rack 31 on the post, so that by operation of this motor the post may be moved vertically for the purpose of lowering the tongs into the mouth of the heating furnace or pit and of raising them therefrom after the ingot of metal has been deposited in the pit or grasped in order to raise it. The head of the tongs is made rotatory on its vertical axis, and for that purpose is swiveled to the end of the post and is connected by gearing 32 to the square or feathered shaft 33, which is preferably driven by hand, so that it may be rotated throughout a whole or a partial revolution, as desired by the operator, in order to enable him to bring the tongs into proper position to grasp the ingot. The shaft 33 may, however, be driven by power, if desired, though I have not found this to be necessary.

The operation of the apparatus when thus constructed is as follows: In Fig. 1 I show the tongs elevated to their highest position. If it is desired to seize an ingot and to carry it to the heating-furnace, the bridge of the crane and the trolley on the bridge are moved so as to bring the tongs above the position of the ingot, and then the post 10 is lowered by the rack and pinion above described until the jaws of the tongs are caused to fit on opposite sides of the ingot, the head of the tongs being turned into proper position for this purpose. Then by operation of the cylinder 18, which moves with the post, the jaws of the tongs are caused to approach, so as to

grasp the ingot firmly. The post is then raised somewhat by the action of the rack and pinion, and the crane-bridge is moved on its track, so as to carry the ingot into a position 5 above the heating-furnace. The post 10 is then lowered further, so as to deposit the ingot in the furnace, whereupon the jaws of the tongs are spread by reverse action of the cylinder, so as to release the ingot, and the post 10 is again raised. If it be desired to shift the position of the ingot in the furnace, and this is a very important and valuable feature of my invention, the ends of the tongs are brought against the ingot and by motion of 15 the trolley or bridge the ingot can be pushed laterally, so as to shift its position as desired. In order that the post may have sufficient rigidity for this purpose, I provide longitudinal guide-bearings 34 on the trolley, which 20 bear against the side of the post and may be provided with antifriction-rollers 35, in order that they may not interfere with the free vertical motion. By these means the post is made as rigid as the trolley, so that without 25 difficulty the ingot may be pushed without straining the post or causing it to bind in its bearings. During the vertical motion of the post the weights 11 act as counterbalances and serve to balance the weight of the post 30 and the tongs, together with the cylinder and their other accessory parts, so that at all times these are in stable equilibrium.

In order to prevent the danger which would result from accidental dropping of the 35 weights, I prefer to use, in addition to the lifting chain which I have described, a safety-chain 36, which will come into action in case the other should break, and in order to steady the weights in their motion I prefer to place 40 them in guides on the outer side of the vertical frame 9.

The advantages of my invention will be appreciated by those skilled in the art.

Within the scope of my invention as defined in the claims modifications in the form, 45 arrangement, and construction of the parts may be made by the skilled mechanic, since

What I claim is—

1. The combination of a traveling crane, a 50 trolley or carriage thereon, a vertically-movable post, and tongs carried by the post, said post having guide-bearings on the trolley and being rendered rigid from said bearings to the point of attachment of the tongs, substantially as described.

2. The combination of a crane, a trolley or

carriage thereon, a vertically-movable post, tongs carried by the post, said post having guide-bearings on the trolley and being rigid from said bearings to the point of attachment 60 of the tongs, and a counterbalance for the post.

3. The combination of a crane, a trolley or carriage thereon, a vertically-movable post set in a frame on the trolley, pulleys in the frame, 65 counterweights for the post having flexible connections passing over said pulleys, and tongs carried by the post, said post being rigid from the frame to the point of attachment of the tongs. 70

4. The combination of a traveling crane, a trolley or carriage thereon, a vertically-movable post, and tongs carried by the post, said post having guide-bearings on the trolley and being rendered rigid from said bearings to 75 the point of attachment of the tongs, substantially as described, and a rack and pinion by which the post is moved vertically.

5. The combination of tongs, a fluid-pressure cylinder for actuating the same, a fluid- 80 reservoir, a pump supplying the same, and a governor which controls the pump and is actuated by the fluid-pressure in the reservoir; substantially as described.

6. The combination of tongs, a fluid-pressure cylinder for actuating the same, a fluid-reservoir, a pump supplying the same, an electric motor which drives the pump, and a governor connected with the reservoir and with the motor-controlling rheostat or switch. 85 90

7. The combination of a traveling crane, a trolley or carriage thereon, a vertically-movable post, and tongs carried by the post, said post having guide-bearings with antifriction-rollers on the trolley and being rendered rigid 95 from said bearings to the point of attachment of the tongs, substantially as described.

8. In an overhead traveling crane, the combination with a traveling trolley, of a rack-bar carried by the trolley, a pinion engaging 100 said rack-bar for moving the same vertically, means for actuating the pinion, guides arranged to hold the bar against lateral movement, and means upon the trolley for regulating the movements of the trolley and rack-bar; substantially as described. 105

In testimony whereof I have hereunto set my hand.

THOMAS JAMES.
